United States Patent Office

Des. 209,141
Patented Nov. 7, 1967

209,141

LIGHT DIMMER CONTROL UNIT

Ernest R. Carlson, Fairfield, Conn., assignor to Harvey Hubbell, Incorporated, Bridgeport, Conn., a corporation of Connecticut

Filed Apr. 1, 1966, Ser. No. 1,736

Term of patent 14 years

(Cl. D26—13)

FIG. 1.

FIG. 2.

FIG. 4.

FIG. 3.

FIG. 1 is a perspective view of a light dimmer control unit embodying my design and showing the front, top and a side thereof;

FIG. 2 is a top plan view thereof;

FIG. 3 is a bottom plan view thereof; and

FIG. 4 is a side elevational view thereof showing the side shown in FIG. 1.

The dominant features of the design reside in the portions shown in full lines.

I claim:

The ornamental design for a light dimmer control unit, substantially as shown and described.
